UNITED STATES PATENT OFFICE

93,803

DESIGN FOR AN ELECTRIC HEATER

Gerrit Van Daam, Buffalo, N. Y.

Application September 15, 1934, Serial No. 53,293

Term of patent 7 years

To all whom it may concern:

Be it known that I, GERRIT VAN DAAM, a citizen of the United States, residing in Buffalo, in the county of Erie, State of New York, have invented a new, original, and ornamental Design for an Electric Heater, of which the following is a specification, reference being had to the accompanying drawing, forming part thereof.

Figure 1 is a view in perspective showing the front.

Figure 2 is an elevation showing the back.

I claim:—

The ornamental design for an electric heater substantially as shown.

GERRIT VAN DAAM.
